(Cl. D67—2)

To all whom it may concern:

Be it known that we, Franklyn Walker Boltz, Florino Ferlisi, Elmer L. Olson, William L. Allinson and Ernest E. Lindsey, citizens of the United States, residing at Los Angeles, San Gabriel, Los Angeles, Los Angeles, Los Angeles, respectively and State of California, have invented a new, original, and ornamental Design for a Combined Freezer and Dispenser for Ice Cream or the like, of which the following is a specification, reference being had to the accompanying drawing, forming a part hereof.

Figure 1 is a perspective view showing the front and one side of a combined freezer and dispenser for ice cream or the like, embodying our new design;

Figure 2 is an elevational view showing the other side thereof; and

Figure 3 is a top plan view thereof.

We claim:

The ornamental design for a combined freezer and dispenser for ice cream or the like, substantially as shown.
